Primary Examiner — Cynthia Ramirez(74) *Attorney, Agent, or Firm* — Polson Intellectual Property Law, PC; Margaret Polson(57) **CLAIM**

The ornamental design for a chassis of a utility cart, as shown and described.

DESCRIPTION

FIG. 1 is a front isometric view of my new design for a chassis of a utility cart.

FIG. 2 is a right side elevation view, the other side being a mirror image thereof.

FIG. 3 is a front elevation view thereof.

FIG. 4 is a back elevation view thereof.

FIG. 5 is a top plan view thereof; and,

FIG. 6 is a bottom plan view thereof

The features shown in broken lines in the drawing depict environmental subject matter only and form no part of the claimed design

1 Claim, 5 Drawing Sheets(56)
